United States Patent Office

Des. 217,159
Patented Apr. 14, 1970

217,159

MAGAZINE RACK OR SIMILAR ARTICLE

William Levy, Glen, N.H., assignor to Standard International Corporation, Andover, Mass., a corporation of Ohio

Filed Apr. 24, 1969, Ser. No. 16,881

Term of patent 14 years

Int. Cl. D6—01

U.S. Cl. D33—2

Fig. 1.

FIG. 3.

FIG. 2.

FIG. 1 is a perspective view of a magazine rack or similar article embodying my new design;

FIG. 2 is a side elevational view thereof; and

FIG. 3 is a front elevational view thereof.

I claim:

The ornamental design for a magazine rack or similar article, substantially as shown.
